MINING APPARATUS

Clyde P. Baldwin, Claremont, N. H., and Harry H. Vanderzee, Michigan City, Ind., assignors to Sullivan Machinery Company, a corporation of Massachusetts

Original application May 21, 1941, Serial No. 394,410. Divided and this application February 24, 1942, Serial No. 432,150.

3 Claims. (Cl. 262—28)

This invention relates to mining apparatus, and more particularly to improvements in a coal mining apparatus of the rubber-tired universal cutter type especially designed for use in trackless coal mining and capable of cutting plane kerfs at various locations in a coal seam.

An object of the present invention is to provide an improved coal mining apparatus. Another object is to provide an improved adjustable kerf cutting mechanism. A still further object is to provide an improved adjustable supporting structure for the kerf cutter of the kerf cutting mechanism of such a mining apparatus whereby plane kerfs may be cut at various locations in a coal seam, with facility. Yet another object is to provide, in a coal mining apparatus of the above character, improved means for rotating the cutter carrying head and for locking the cutter carrying head in its different positions of adjustment. Still another object is to provide an improved coal mining apparatus having novel combinations and arrangements of parts. Further objects and advantages of the invention will become apparent as the description proceeds.

This application is a division of our copending application Serial No. 394,410, filed May 21, 1941. Certain features originally claimed in this application and relating to the improved hydraulically operated cutter bar adjusting and swinging means with the improved operating fluid supply arrangements therefore are being claimed in our copending divisional application Serial No. 635,678, filed December 18, 1945.

In the accompanying drawings there is shown for purposes of illustration one form which the invention may assume in practice.

In these drawings:

Fig. 1 is a plan view of the improved coal mining apparatus, with a portion of the top cover broken away to illustrate structural details.

Fig. 2 is a side elevational view of the coal mining apparatus shown in Fig. 1.

Fig. 3 is an enlarged cross sectional view taken substantially on line 3—3 of Fig. 1.

Fig. 4 is a horizontal sectional view taken substantially on line 4—4 of Fig. 3.

Fig. 5 is an enlarged vertical sectional view taken substantially on line 5—5 of Fig. 1.

Fig. 6 is an enlarged horizontal sectional view taken substantially on line 6—6 of Fig. 2.

Fig. 7 is an enlarged fragmentary plan view of a portion of the kerf cutting mechanism shown in Fig. 1.

Fig. 8 is a side elevational view of the structure

shown in Fig. 7, with a portion broken away in vertical section to illustrate structural details.

Fig. 9 is a cross sectional view taken substantially on line 9—9 of Fig. 8.

5 Fig. 10 is an enlarged cross sectional view taken substantially on line 10—10 of Fig. 1.

In this illustrative embodiment of the invention there is shown a coal mining apparatus of the rubber-tired universal type especially designed for use in trackless coal mining. It will be evident, however, that various features of the invention may be embodied in coal mining apparatus of various other types, and, if desired, the apparatus may be mounted on track wheels to travel along a mine trackway or may be tractor-tread mounted.

The coal mining apparatus as disclosed is mounted on relatively large pneumatic rubber-tired wheels adapted to run along the floor of a mine without the aid of a guiding trackway, and has universally mounted kerf cutting mechanism capable of cutting plane kerfs at various locations in a coal seam, with comparative ease and efficiency. Since the apparatus is mounted

20 to run on rubber-tired wheels which directly engage the mine floor, the apparatus is not dependent on a guiding trackway, and, therefore, may be maneuvered in any desired direction and located at any desired point with respect to the coal face and ribs; and the apparatus may be propelled by the rubber-tired traction wheels both during maneuvering and during the kerf cutting operation.

The coal mining apparatus herein constitutes 35 an improvement over that disclosed in our copending application Serial No. 578,084, filed February 15, 1945, which is a division of our earlier filed application Serial No. 378,728, filed Feb. 13, 1941, and generally comprises a main frame or body 1 mounted on front rubber-tired traction

40 wheels 2 and rear rubber-tired steering wheels 3. The main frame or body carries at its forward end universally adjustable kerf cutting mechanism, generally designated 4, including a kerf cutter 5. The front traction wheels 2 have driving means, generally designated 6, 6, while associated with the rear steering wheels is fluid actuated steering mechanism, generally designated 7.

45 A motor 8 drives the kerf cutter, while a separate motor 9 drives a pump 10 of the hydraulic system, and the latter embodies control valve mechanism, generally designated 11.

50 The kerf cutting mechanism 4 is generally similar to that disclosed in the copending application Serial No. 578,084, above referred to, and com-

prises a horizontal turntable 12 carried at the front end of the main frame or body 1 intermediate the front traction wheels 2, in the manner shown in Fig. 1; and pivotally mounted on this turntable, to swing in a vertical direction relative thereto is an elongated arm structure or boom 13. The arm structure or boom overlies the turntable and extends forwardly in advance of the forward end of the main frame or body, and the forward portion of the boom carries a rotatable cutter carrying head 14 which constitutes an outer extension of the boom. The cutter carrying head is mounted to rotate about the longitudinal axis of the boom and has a rotatable front neck frame 15 journaled on bearings on the non-rotatable rear boom frame 16. Pivotally mounted at 17 on the forward portion of the rotatable neck frame 15 is a cutter support 18, the latter being swingable relative to the neck frame about an axis at right angles to the axis of head rotation. The cutter support 18 of the rotatable cutter carrying head 14 has pivotally mounted thereon to swing about the axis 19 a cutter carrying hanger frame 20, the latter being swingable relative to the cutter support about an axis at right angles to the cutter support pivot axis. The kerf cutter 5 is carried by the hanger frame 20 and comprises an elongated plane cutter bar 21 having guided for circulation about its margin an endless cutter chain 22. The motor 8 is arranged at the rear portion of the boom 13, and the casing 23 of this motor constitutes the rearward portion of the boom frame 16. This motor is preferably of the electric type and preferably has its armature shaft arranged with its axis of rotation coincident with the axis of rotation of the cutter carrying head 14 and is operatively connected to the cutter chain 22 to drive the latter, in the manner fully described in the copending application Serial No. 578,084, mentioned above, so that the cutter chain may be driven irrespective of the position of the cutter carrying head 14 about its axis, the tilted position of the cutter support 18, or the swivelled position of the bar hanger frame 20.

For swinging the boom 13 in a vertical direction about its pivot relative to the turntable 12 and for locking the boom in its adjusted position, there are provided, at the opposite sides of the boom, upright hydraulic cylinders 24, while mounted on the neck frame 15 of the cutter head is a hydraulic cylinder 25 for tilting the cutter support about its pivot relative to the neck frame and for locking the cutter support in its adjusted position. Also mounted on the neck frame, at the opposite sides of the latter, are hydraulic cylinders 26, 26 for swinging the bar hanger frame 20 about its pivotal axis with respect to the cutter support and for holding the bar hanger frame in its adjusted position. These hydraulic cylinders and their operative connections with the devices swung thereby are likewise fully described in the copending application Serial No. 578,084, above referred to, and further mention thereof will be made later.

The means for rotating the cutter carrying head 14 about the longitudinal axis of the boom 13 may assume various forms, and as herein shown comprises a conventional hydraulic motor 27 mounted on the motor casing 23 at the rear end of the boom. This motor is of the reversible type and has its power shaft keyed to a worm shaft 28 (Fig. 3) herein suitably journaled within a housing 29 secured to the rear end of the boom. The worm 30 of the worm shaft meshes with a worm wheel 31 (see also Fig. 4) keyed to a longi-

tudinal shaft 32 likewise suitably journaled within the gear housing. Secured to and driven by the shaft 32 is a spur gear 33 meshing with a spur gear 34, the latter having its hub fixed to a longitudinal shaft 35. The shaft 35 is suitably journaled within the housing and is keyed at 36 to an alined shaft 39 which extends longitudinally over the top of the motor casing, as shown in Fig. 1, and is suitably journaled in bearings supported by the boom. Fixed to the forward end of the shaft 39, as shown most clearly in Fig. 5, is a chain sprocket 40 connected by an endless drive chain 41 to a large chain sprocket 42 (Fig. 8) the latter herein keyed to the rearward portion of the rotatable neck frame 15 of the cutter carrying head and surrounding the axis of head rotation. The upper portion of the drive chain 41 is guarded by a housing 43, and the forward end of the shaft 39 is journaled in an outboard bearing 44 supported by this housing (Fig. 5). The teeth of the worm gears 30, 31 are self-locking and serve to lock automatically the cutter head in its different positions of adjustment. As shown in Fig. 10, rotation of the cutter carrying head with respect to the boom is limited by a stop lug 45 secured to the neck frame and engageable with a stop lug 46 formed on an end plate 47 secured to the non-rotatable rearward portion 16 of the boom. Mounted on the main frame or body 1 at the opposite sides of the turntable 12 are hydraulic cylinders 48, 48 (Fig. 1) containing reciprocable pistons having their piston rods 49 pivotally connected to lateral lugs integral with the turntable 12 for rotating the turntable, thereby to swing the boom structure in a horizontal direction, in a manner likewise described in the copending application Serial No. 578,084, above referred to. When the liquid is trapped within these hydraulic cylinders, the turntable may be locked in its different positions of adjustment.

The driving means 6, 6 for the front traction wheels 2 includes reversible hydraulic motors 50, 50 mounted at the opposite sides of the main frame or body 1 just rearward of the front traction wheels. These motors each drive a chain sprocket 51 connected by an endless drive chain 52 to a chain sprocket 53, one secured to the hub of each front traction wheel. As fully described in application Serial No. 394,410, there is a plural speed transmission means associated with each of the hydraulic motors 50, 50, and it is accordingly evident that the front traction wheels may be driven by the hydraulic motors 50 through the plural speed transmission means at relatively high maneuvering speeds or at relatively low speeds appropriate for cutting.

The novel fluid conducting means associated with the rotatable cutter carrying head includes conduits 54, 55, 56 and 57 to which liquid under pressure is supplied from the pump 10 under the control of the control valve mechanism 11, and these conduits are arranged in a novel manner with respect to the rotatable neck frame 15 of the cutter carrying head 14. The conduits 54 and 55 are respectively connected to the opposite ends of the bar swinging cylinders 26, while the conduits 56 and 57 are connected to the opposite ends of the cutter support tilt cylinder 25. As shown in Figs. 7, 8 and 9, the conduits 54, 55, 56 and 57 are secured by a clamp plate 58 to the top of the boom; these conduits extending over the top of the boom and having their forward portions secured by a clamp plate 59 to the rotatable neck frame 15. Intermediate the conduit portions on the top of the boom and the conduit portions on

the rotatable neck frame are flexible conduit portions or bights 60, 61, 62 and 63, and these flexible portions partially encircle the neck frame at the opposite sides of the latter in the manner shown in Fig. 9. These flexible conduit portions permit rotation of the cutter head with respect to the boom within the limits provided by the stop lugs 45, 46 (see Fig. 10). A guide bracket 64, secured to the boom frame 15, serves as a guide for the central loop portions of the flexible conduit portions 60, 61, 62 and 63. It is accordingly evident that by the provision of the particular arrangement of the supply connections with respect to the neck frame of the cutter carrying head, liquid under pressure may be supplied to the cutter support tilt cylinder 25 and the cutter bar swing cylinders 26, 26 irrespective of the position of the cutter carrying head about the longitudinal axis of the boom. The pump 18 also may supply liquid under pressure, under the control of the valve mechanism 11, to the opposite ends of the boom swing cylinders 48 and the boom lift cylinders 24, and to the head rotating motor 27 in the manner also fully described in our copending application Serial No. 394,410.

The mode of operation of the improved coal mining apparatus is essentially the same as that fully described in our copending application Serial No. 578,084, mentioned above. The apparatus may be propelled about the mine at relatively high traveling speeds or may be propelled at relatively slow speeds appropriate for cutting by the traction wheel driving means 6, 6, and steering of the apparatus may be effected by the fluid actuated steering mechanism 7 under the control of the valve mechanism 11. During the kerf cutting operation liquid under pressure may be supplied to the hydraulic cylinders 24, 25, 26 and 48 and to the head rotating motor 27 under the control of the control valve mechanism 11 to effect adjustment of the kerf cutter into the desired cutting position and to effect movement of the kerf cutter during the kerf cutting operation. The turntable rotating cylinders 48 may be operated to swing the cutter supporting boom laterally, and the cutter swinging cylinders 26 may be operated to swing the cutter about its pivot relative to the boom. The cylinders 24 may be operated to swing the boom in a vertical direction relative to the turntable while the cylinder 25 may be operated to tilt the cutter support relative to the neck frame. The head rotating motor 27 may be operated to turn the cutter carrying head about the longitudinal axis of the boom to locate the kerf cutter in either vertical, horizontal or any desired intermediate cutting positions. When liquid is trapped in the various hydraulic cylinders, the parts adjusted thereby may be locked in their adjusted positions. The cutter carrying head may be rotated relative to the rearward portion of the boom by the motor 27 under the control of the valve mechanism 11 and head rotation is

effected through the gearing 30, 31, 33, 34, shafts 35 and 39 and the chain and sprocket connection 40, 41, 42, and when the supply of liquid to the head rotating motor is cut off the self-locking teeth of the worm gears 30, 31 serve to hold the cutter head in its position of adjustment. Since the general mode of operation of a coal mining apparatus of the character disclosed is fully described in our copending application Serial No. 578,084, above mentioned, further description of the mode of operation of the apparatus is herein unnecessary.

While there is in this application specifically described one form which the invention may assume in practice, it will be understood that this form of the same is shown for purposes of illustration and that the invention may be modified and embodied in various other forms without departing from its spirit or the scope of the appended claims.

What we claim as new and desire to secure by Letters Patent is:

1. In a mining apparatus, kerf cutting mechanism including a swingable boom, a cutter carrying head mounted on said boom, and motor operated means for rotating said head and for locking said head in its different positions of adjustment including a motor carried at the rear end of said boom, and connections between said motor and said head including a shaft extending along said boom, a rotating member fixed to said shaft at the front end thereof, and bearings for the front end of said shaft at the opposite side of said rotating member.
2. In a mining apparatus, a support, a cutter carrying head journaled on said support, and means for rotating said head including a drive shaft on said support, a chain sprocket on said shaft near the front end thereof, a large chain sprocket on said head and surrounding the head axis, and an endless drive chain connecting said sprockets in driving relation, and bearing means for the front end of said shaft including bearings at the opposite sides of said first mentioned chain sprocket, said endless drive chain extending between said shaft bearings.
3. In a mining apparatus, a support, a cutter carrying head journaled on said support, and means for rotating said head including a drive shaft on said support, a rotatable transmission element on said shaft near the front end thereof, a rotatable transmission element on said head and surrounding the axis of head rotation, a flexible endless transmission connection between said rotatable transmission elements, and bearing means for the front end of said shaft including shaft bearings at the opposite sides of said first mentioned rotatable transmission element, said flexible transmission connection extending between said shaft bearings.

CLYDE P. BALDWIN.
HARRY H. VANDERZEE.
